(57) **CLAIM**

The ornamental design for a desk as shown and described.

DESCRIPTION

FIG. 1 is a perspective view of a desk showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 1;

FIG. 12 is an enlarged view of portion 12 shown in FIG. 1;

FIG. 13 is an enlarged view of portion 13 shown in FIG. 2;

FIG. 14 is an enlarged view of portion 14 shown in FIG. 2;

FIG. 15 is an enlarged view of portion 15 shown in FIG. 2;

FIG. 16 is an enlarged view of portion 16 shown in FIG. 2;

FIG. 17 is an enlarged view of portion 17 shown in FIG. 2;

FIG. 18 is an enlarged view of portion 18 shown in FIG. 2;

FIG. 19 is an enlarged view of portion 19 shown in FIG. 3;

FIG. 20 is an enlarged view of portion 20 shown in FIG. 3;

FIG. 21 is an enlarged view of portion 21 shown in FIG. 3;

FIG. 22 is an enlarged view of portion 22 shown in FIG. 3;

FIG. 23 is an enlarged view of portion 23 shown in FIG. 3;

FIG. 24 is an enlarged view of portion 24 shown in FIG. 4;

FIG. 25 is an enlarged view of portion 25 shown in FIG. 4;

FIG. 26 is an enlarged view of portion 26 shown in FIG. 4;

FIG. 27 is an enlarged view of portion 27 shown in FIG. 4;

FIG. 28 is an enlarged view of portion 28 shown in FIG. 5;

FIG. 29 is an enlarged view of portion 29 shown in FIG. 5;

FIG. 30 is an enlarged view of portion 30 shown in FIG. 5;

FIG. 31 is an enlarged view of portion 31 shown in FIG. 6;

FIG. 32 is an enlarged view of portion 32 shown in FIG. 6;

FIG. 33 is an enlarged view of portion 33 shown in FIG. 6;

FIG. 34 is an enlarged view of portion 34 shown in FIG. 7;

FIG. 35 is an enlarged view of portion 35 shown in FIG. 8;

FIG. 36 is an enlarged view of portion 36 shown in FIG. 8;

FIG. 37 is an enlarged view of portion 37 shown in FIG. 8;

and,

(Continued)

FIG. 38 is an enlarged view of portion 38 shown in FIG. 8. The dash-dash broken lines in the drawings depict portions of the desk that form no part of the claimed design. The dot-dash broken lines represent boundaries of the enlarged portions and form no part of the claimed design.
